UNITED STATES PATENT OFFICE.

WILLIAM C. HOOKER, OF ABINGDON, ILLINOIS.

GATE.

SPECIFICATION forming part of Letters Patent No. 515,430, dated February 27, 1894.

Application filed July 25, 1893. Serial No. 481,448. (No model.)

To all whom it may concern:

Be it known that I, WILLIAM C. HOOKER, a citizen of the United States, residing at Abingdon, in the county of Knox and State of Illinois, have invented a new and useful Gate, of which the following is a specification.

The invention relates to improvements in gates.

The object of the present invention is to improve the construction of gates, and to provide a simple and inexpensive swinging gate, which may be readily opened and closed without leaving a vehicle or dismounting, and in which the mechanism for operating the gate at a distance will not interfere with the opening and closing of the gate by a person on foot.

The invention consists in the construction and novel combination and arrangement of parts hereinafter fully described, illustrated in the accompanying drawings and pointed out in the claims hereto appended.

In the drawings—Figure 1 is a perspective view of a gate constructed in accordance with this invention. Fig. 2 is a reverse plan view partly in section of the operating mechanism, showing the position of the parts when the gate is closed. Fig. 3 is a horizontal sectional view of the operating mechanism showing the position of the parts when the gate is open, before the semi-rotating actuating frame has returned to its normal position. Fig. 4 is a vertical sectional view of the operating mechanism. Fig. 5 is a detail sectional view showing the weighted pawl in engagement with the plate of the rotating arm which is connected with the gate. Fig. 6 is a detail perspective view of the semi-rotating actuating frame. Fig. 7 is a similar view of the plate of the rotating arm. Fig. 8 is a detail view of the pivoted bar showing the stop. Fig. 9 is a detail perspective view of the upper rear end of the gate, showing the brace.

Like numerals of reference indicate corresponding parts in all the figures of the drawings.

1 designates a swinging gate hinged to a post 2 and connected between its ends by a rod 3 with a revolving arm 4, which is pivotally mounted on a post or other support 5, and which is adapted at every half revolution to swing the gate between a latch post 6 and a supplemental latch post 7 to open and close

the gate. The support 5 is provided at its top with a vertical pivot 8; the inner end of the revolving arm 4 has a perforation receiving the pivot; and on the latter beneath the revolving arm 4 is mounted an actuating frame 9 with which are connected operating ropes 10. The operating ropes are adapted to actuate the frame 9 a half revolution, which opens or closes the gate, and it is returned to its normal position by a spiral spring 11 in order that after returning to such initial position it may be again moved a half revolution by the operating ropes to actuate the revolving arm 4 a half revolution to open or close the gate. One half of a revolution of the revolving arm 4 opens the gate, and the next half of the revolution closes it. The spiral spring 11 has its lower end connected with the support by a stop 12, and its upper end is secured to the actuating frame 9, which carries a pivoted weighted pawl 13 for engaging diametrically oppositely disposed teeth 14 of the revolving arm 4, whereby the latter is connected with and carried by the actuating frame. The teeth 14 of the revolving arm are located on opposite sides of the pivot 8, and may be formed of any suitable means, but are preferably constructed by recessing and beveling the ends of a plate 15, which is secured to the lower face of the revolving arm, and which is provided with a pivot opening to receive the pivot 8. The weight of the pawl 13 is arranged on the opposite side of the fulcrum point or pivot point from the engaging head, and is adapted to hold the latter in engagement with the revolving arm 4; but when the spiral spring returns the actuating frame to its initial position, the weight of the pivoted pawl is engaged by the stop, and is lifted for holding the pawl out of engagement with the revolving arm 4, and for leaving the latter perfectly free to turn, whereby the gate may be opened or closed by a person on foot without actuating the operating mechanism for opening and closing the gate at a distance. The pawl is pivoted or fulcrumed by means of trunnions or journals formed integral with it and arranged in bearing recesses of the actuating frame.

The actuating frame is provided at diametrically opposite points with lateral extensions 16 to each of which is connected a pair of

pivoted bars 17 and 18, which are normally arranged at substantially right angles, but which, when an operating rope is pulled, are adapted to swing around and to straighten as 5 illustrated in Fig. 3 of the accompanying drawings; and they afford means of connecting the inner adjacent ends of the operating ropes, wires or the like, with the opposite sides of the actuating frame, whereby by pulling on the operating rope the actuating frame may be moved a half revolution. The pivoted bars 17 and 18 may straighten, but are held against moving toward each other and forming less than a right angle, by stops 19 consisting preferably of a 15 keeper having a shoulder arranged to engage the inner side of the bar 18 at the inner pivoted end thereof. By this construction, when an operating rope is pulled, the actuating frame is moved a half revolution carrying 20 with it the revolving arm 4; and after the completion of a half revolution on releasing the operating rope, the spiral spring returns the actuating frame to its normal position. By this means the ends of the plate 15 are alternately engaged by the pivoted pawl to 25 cause the arm 4 to rotate in semi-revolutions. The inner end of the revolving arm 4 is covered by a cap plate 20, which protects the operating mechanism, and which is preferably 30 circular and concavo-convex. The operating ropes extend a suitable distance from opposite sides of the gate and are provided with handles which depend from hangers of uprights 21; and the hangers are provided with 35 pulleys 22 to enable the rope to be readily pulled. The rod 3, which has one end connected with the revolving arm 4, has its other end connected with an upper arm of a rock-shaft 23, which is journaled on a vertical bar 40 24 of the gate, and which has a lower arm connected with a latch 25. The latch 25 is adapted to engage keepers of the latch and supplemental latch posts, and is approximately L-shaped, and is provided at the top with a coil 45 to impart resiliency to it to enable it to automatically engage the keepers, and to hold the gate open and closed. By connecting the rod 3 with the rock-shaft the latch is withdrawn from engagement with the keepers as soon as 50 the operating ropes are pulled. The bar 24 of the gate is extended vertically to bring the upper end of the rock-shaft in the same horizontal plane as the revolving arm 4.

The gate is provided with a rearwardly and 55 upwardly inclined brace 26, consisting of strands of wire, and having its lower end secured to the bottom of the gate at about the middle thereof. The upper end of the wire brace passes through an inclined perforation 60 27 at the top of the gate at the inner end thereof, and is provided with a ring 28 and a washer 29; the ring is adapted to be turned to twist the wire to counteract any sagging; and the washer forms a bearing for the ring. 65

The actuating frame preferably consists of a circular plate or casting, and the lateral extensions 16 are preferably formed by bars se-

cured to the circular plate or casting; but the whole may be a single casting. The bearing recess for the pawl 13 is made in the upper 70 face of an outwardly projecting portion or lug 30; and two of these lugs or projections 30 are provided and are arranged on opposite sides of one of the lateral extensions 16 to enable the mechanism to be applied without change 75 to a gate swinging in one direction or the other. To this end the plate 15 is provided at each end with opposite teeth 14 formed by beveling a longitudinal extension at each side.

It will be seen that the gate is simple and 80 comparatively inexpensive in construction and easily operated, that the operating mechanism is positive and reliable, and that it does not interfere with opening by hand by 85 persons on foot.

Changes in the form, proportion, and the minor details of construction may be resorted to without departing from the principle or sacrificing any of the advantages of this invention. 90

What I claim is—

1. The combination of a swinging gate, a support, a horizontally disposed revolving arm mounted on the support and connected with the gate, and capable of opening and closing the same, and a semi-rotating actuating frame mounted on the support and provided with a pawl detachably engaging the arm, substantially as described. 95

2. The combination of a swinging gate, a support, a revolving arm pivotally mounted on the support and connected with the gate, a semi-rotating actuating frame provided with a pawl for engaging the revolving arm, said pawl being pivoted and weighted to hold it 100 in engagement with said arm, and a spring for returning the actuating frame to its initial position, substantially as described. 105

3. The combination of a swinging gate, a support, a revolving arm mounted on the support and connected with the gate, a semi-rotating actuating frame mounted on the support, a stop, a pivotally mounted and weighted pawl carried by the actuating frame and adapted to engage the revolving arm and arranged to be engaged by the stop to lift its weight, and to release it or to hold it out of engagement with the revolving arm when the actuating frame is returned to its initial position, and a spring for returning the frame to 115 its initial position, substantially as described. 120

4. The combination of a swinging gate, a support provided with a vertical pivot, a horizontal revolving arm mounted on the pivot and connected with the gate, a stop arranged 125 on the support and located adjacent to the pivot and projecting above the support, a semi-rotating actuating frame mounted on the pivot and arranged beneath the revolving arm, a pivotally mounted pawl carried by the 130 actuating frame and provided at one side of the pivot with a head to engage the revolving arm and at the other side of the pivot with a weight arranged to engage the stop, a spiral

spring disposed on the pivot and connected with the actuating frame and adapted to return the same to its initial position, and a plate secured to the revolving arm and provided at its end with teeth to be engaged by said pawl, substantially as described.

5. The combination of a swinging gate, a support, a revolving arm mounted on the support, a semi-rotating actuating frame arranged to engage the revolving arm to rotate the same in semi-revolutions, and the angularly disposed bars arranged in opposite pairs, the inner bar of each pair being pivoted to the actuating frame and the outer 15 bar of each pair being adapted to swing outward and to straighten to semi-rotate the actuating frame and being designed to be connected to an operating rope, substantially as described.

20. 6. The combination with a swinging gate, a support, a revolving arm mounted on the support and connected with the gate, a semi-rotating actuating frame mounted on the support and arranged to engage the revolving arm, the pivoted bars arranged in pairs and disposed at an angle when the frame is in its initial position, the inner bars of the pairs being pivotally connected to the actuating frame at diametrically opposite points and 25 provided at their outer ends with stops to engage the inner edges of the outer bars to limit the inward swing of the said outer bars, the latter being designed to be connected with operating ropes, and means for returning the 30 frame to its initial position, substantially as described.

7. The combination of a swinging gate, a support provided with a vertical pivot, a revolving arm mounted on the pivot and connected with the gate, a semi-revolving actuating frame mounted on the pivot and provided with a pawl for engaging the revolving arm, a spring for returning the actuating frame to its initial position, and the angularly disposed bars arranged in opposite 40 pairs and designed to have operating ropes connected with them and adapted to swing outward to straighten to semi-rotate the actuating frame against the action of the spring, the inner bars of the pairs being provided with stops for limiting the inward swing of 45 the outer bars to hold the latter at an angle, substantially as and for the purpose described.

8. The combination of a swinging gate, a support, a revolving arm mounted on the support and connected with the gate, a plate secured to the revolving arm and provided at each end with opposite teeth, a semi-rotating actuating frame mounted on the support and 50 provided with opposite bearings 30, and a weighted pawl adapted to be arranged in either of said bearings to engage said plate, and a spring for returning the actuating frame, substantially as described. 55

In testimony that I claim the foregoing as my own I have hereto affixed my signature in the presence of two witnesses.

WILLIAM C. HOOKER.
